(57) **CLAIM**

The ornamental design for an intravascular lithotripsy catheter, as shown and described.

DESCRIPTION

FIG. 1 is a top perspective view of an intravascular lithotripsy catheter;

FIG. 2 is a bottom perspective view of the intravascular lithotripsy catheter illustrated in FIG. 1;

FIG. 3 is a top view of the intravascular lithotripsy catheter illustrated in FIG. 1;

FIG. 4 is a left side elevation view of the intravascular lithotripsy catheter illustrated in FIG. 1;

FIG. 5 is a right side elevation view of the intravascular lithotripsy catheter illustrated in FIG. 1;

FIG. 6 is a bottom view of the intravascular lithotripsy catheter illustrated in FIG. 1;

FIG. 7 is an end view of the intravascular lithotripsy catheter illustrated in FIG. 1; and,

FIG. 8 is an opposite end view of the intravascular lithotripsy catheter illustrated in FIG. 7.

The surface shading and broken lines in the drawings illustrate portions of the intravascular lithotripsy catheter and form no part of the claimed design.

1 Claim, 6 Drawing Sheets
